United States Patent

Des. 237,990
Patented Dec. 9, 1975

237,990

TENNIS RACQUET

Monte C. Gillespie, and Darle L. Kerkenbush, South Bend, Ind., assignors to South Bend Toy Manufacturing Company, Inc., South Bend, Ind.

Filed Nov. 8, 1974, Ser. No. 522,096

Term of patent 14 years

Int. Cl. D21—02

U.S. Cl. D34—5 ST

FIG. 1.

FIG. 2.

FIG. 3.

FIG. 4.

FIG. 5.

FIG. 1 is a top plan view of a tennis racquet showing our new design;

FIG. 2 is a side elevational view thereof;

FIG. 3 is a cross-sectional view taken on line 3—3 of FIG. 1; and

FIGS. 4 and 5 are cross-sectional views taken on lines 4—4 and 5—5 respectively, of FIG. 3.

We claim:

The ornamental design for a tennis racquet, as shown and described.
